LOOSE SHEET BINDER

Application filed October 3, 1931. Serial No. 566,697.

This invention relates to an improvement in loose sheet binders. It is quite old in this art to provide a binder with prongs or rings to hold the sheets and to notch the folded edges of the sheets to straddle the prongs and to have removable wires inserted in the folded edges underlying the prongs to hold the sheets in place. The advantage of this arrangement is that individual sheets or 10 groups of sheets can be inserted and removed without disturbing the other sheets in the binder. By removing a particular wire the folded sheet or group of sheets held by that wire can be lifted from the center or any 15 other part of the binder and not disturb any of the other sheets. So far as I know, this idea has never been available in loose leaf binders having extensible backs to vary the contents of the binder while giving a neat appearance.

According to one feature of my invention I provide means by which a loose leaf binder having an extensible back can be used with convenience when the sheets are notched and 25 held in place by wires for individual sheet or group manipulation when inserted or removed from the binder. To provide such a binder there are certain difficulties which need to be overcome by special construction. 30 I have found in working out such special construction that there are certain advantages in it applicable to an improved binder even though it does not have an extensible back. These improvements will all be 35 closed in connection with the accompanying drawing.

Fig. 1 is a longitudinal sectional view through the back of a loose sheet binder showing the nature of one type of extensible back, 40 and how one of the removable wires is arranged under the prongs, and in the folds of a group of loose sheets so as to hold the latter in the book. Parts are indicated as cut away to give a larger scale in this view;

Fig. 2 shows a transverse section through a part of the binder taken on the line 2—2 of Fig. 1, but with only a few sets of folded sheets in place for illustrative purposes;

Fig. 3 shows a detail of construction in 50 which a sheet perforating device is built into

the binder and proportioned for the sheets of the particular binder; and

Fig. 4 is an end view of the extensible binder as it will appear when filled with sheets between its minimum and maximum capacity.

The particular type of extensible back binder chosen for purposes of illustration is in general well known in the art. It consists of side covers 1 and 2, and an extensible back of two parts. One part comprises the side 3 and bottom 4; the other part, the side 5 and bottom 6. The bottom portions 4 and 6 overlap for adjustable purposes, as shown in Fig. 2. A strap metal frame 7 with right angle bends at the ends is fastened by anchors 9 to side 5 and a similar frame 8 is fastened to side 3. These frames 7 and 8 at their opposite right angle bends are overlapped so that one is received into a channel of the other in slidably overlapping relation at each end, as indicated in the section of Fig. 3. At each end also, the channel part has a slot 10 (Fig. 4) determining the extensible degree of the back. When the back is adjusted to its minimum capacity corresponding ends of these slots 10 are positioned so that threaded openings in the end pieces of frame 7 are in line to receive small bolts 11 located at the ends of the slots. As the back is extended the bolts slide in the slots and the back is fastened to the desired adjustment by tightening bolts 11. The heads of the bolts 11 are conveniently made round and slotted so as to be turned by a coin. The construction is called a coin lock. The threaded openings in frame 7 are conveniently made by nuts 12 soldered to the frame in line with a hole punched in the frame. From this construction it is clear that the back of the binder is formed into a transversely adjustable and shallow rectangular box with the overlapped ends of frame members 7 and 8 forming the end sides of the box, and the overlapped portions 4 and 6 forming the bottom. The side covers 1 and 2 of the binder are flexibly hinged to the longitudinal edges of the back at the top of their side portions.

The frame 7 carries spaced metal prongs

14 and frame 8 carries prongs 13 offset with respect to prongs 14. Each of these prongs has a leg to fasten to its frame and a bent portion to overhang the top of the box-like back with the free end extending almost to the opposite side of the back when the latter is adjusted to its minimum capacity and in any event to overlap, across the top of the back, the prongs whose free ends extend from 10 the opposite side.

It is customary in such an extensible binder (and in others known in the trade) to insert loose sheets with round holes punched at their binding edges so that the sheets are 15 held threaded on the prongs. It will be readily appreciated that in this kind of a book there is a lot of manipulating to be done, particularly when adjusting it in its extensible back features, inserting loose 20 sheets and taking them out and taking care to finally lock the book in condition for a neat appearance. Such an appearance is indicated in Fig. 4.

On account of the manipulation necessary, 25 it is not unusual, particularly in binders of the extensible class, to find that they are used without taking advantage of their compacting or expansible function according to the number of sheets actually held therein from 30 time to time. According to one feature of my invention I have provided means to cut down the amount of manipulation required in extensible binders so as to invite a better use of such books.

35 I accomplish this means by inserting and removing the sheets on the prongs in a different way and by providing means to cooperate with the sheets and prongs to removably hold them in proper relation. The 40 last named means I have developed with especial regard to the fact that in an extensible binder there is usually much more transverse movement of the sheets in the binder back during manipulation, than 45 where the binder is of fixed capacity. I will describe this matter in detail.

Instead of providing holes for threading the loose sheets on prongs 13 and 14, I cut notches in the folded edges of loose sheets. A 50 single folded sheet or a group, as shown in the drawings, is quickly inserted with the notches arranged to straddle the prongs. I then slip a flexible metal wire 16 along the bottom fold of the loose sheet or the inner- 55 most fold of a plurality of loose sheets so as to close up the notches 15. By this construction the sheets can be taken out or inserted in the binder in any arrangement or relative position desired and all so easily that the 60 binder can be filled or adjusted to the desired capacity without taking the filler all apart to make the arrangement wanted. I have found by experimenting with different arrangements of wire holding means in their relation 65 to the binder that it is of considerable ad-

vantage to removably attach the wire to the loose sheet or sheets in the fold of which the wire lies and not leave it loose to move endwise. A preferable way of attaching the wire is to make a bend in the end at 17 and pass a 70 vertical portion as at 18 through a perforation in the fold of the sheet. The bend 17 serves as a convenient finger hold in the manipulation of the wire to insert it under the prongs, to remove it, and to removably attach it to the folded sheet by inserting portion 18 in its small hole. With the wire attached to the loose sheet in this manner it is free to slide transversely with the sheets on the prongs for easy adjustability in the extensible back feature of the binder, and the notches are made large enough for this purpose. But by attaching the wires 16 to the sheets, one for each folded sheet or group of 75 sheets, they cannot slip endwise and extend out beyond the ends of the sheets. With these features present in the construction the disadvantage of having the holding wires loosely mounted in the binder with a tendency to 80 shift around and out of place is avoided. And it is avoided not by tightening the wires by pressing or removably fastening them to the prongs 13 and 14 which might seem an 85 easy solution. That would prevent the desired free movement of sheets on the prongs which would interfere with the extensible 90 character of the binder in its easy manipulation.

The arrangement described is shown in 95 Figs. 1 and 2. In the latter figure only three sets of sheets and three metal wires are shown to avoid crowding the illustration. In some instances it may be desirable to bend wires 16 without providing any finger grip portion but only a portion to interfit with the perforation. In such a case of course the ends of wires 16 have a simple right angle bend.

In Fig. 3 I have shown a convenient means 100 of piercing the loose sheets for receiving portions 18. A steel piece 20 is pivoted at 21 on frame 8, to swing into upright position and to swing back out of the way. A stop 21 limits the swinging movement of piece 20 so as to present its sharpened prong 22 at one edge, a fixed distance above the straight edge 105 23 of frame 8. A folded sheet is mounted to rest on straight edge 23 pulled back toward 20, with the fold of the sheet in line to be pierced at the right place for portion 18 of a wire to attach itself. When not in use steel piece 20 is turned down with prong 22 buried 110 between frame 8 and the side 3 of the binder back. It is a convenience to have the binder carry this piercing tool in view of the desire 115 to have wires 16, the loose sheets, and prongs 14 all uniformly and neatly fitted in predetermined relationship. But the piercing of the 120 sheets can be done at the time the notches are made or by sharpening the end portion 18 of each wire 16, to do its own piercing.

By the arrangement described, as seen in Fig. 4, an exceedingly neat binder with an extensible back is provided. The outer appearance of the binder has not been affected in any way by the construction and arrangement for inserting and removing the sheets. To outward appearance the binder shown in Fig. 4 is one which has been assembled with its loose sheets to give the neatest possible appearance in the old way. But with its interior features of construction shown in the other figures it has many new and useful advantages.

Some of these advantages are as follows:

The attaching of the retaining wire to the sheets to be retained makes a neater assembly in the binder. The absence of all end-wise movement of the wires in the folded sheets permits the latter to move without any possible interference or scraping of the wire ends on the binder parts or dislodgment of the wires. The extensible feature of the binder back combined with notched sheets and retaining wires enables the extensible binder to be more readily made up in neat and compact form and in accordance with the contents thereof. The improved binder can be filled in the old way with perforated sheets held on the prongs where that is desired for any reason, and inserts can be placed in or removed from any part of such a book by retaining wires as described, the extensible feature of the binder being designed to better accommodate this kind of a combined use.

What I claim is:

A loose sheet binder comprising side covers and a back, a plurality of prongs, some secured to one side and some to the other side of said back, a plurality of sets of sheets, the sheets of each set folded together and notched along the fold, said prongs engaging the respective notches, in combination with spring metal retaining wires one for each set of sheets and each extending under said prongs and along the folded line of its set to close the notches, each retaining wire being straight except at one end and at such end having a downwardly extending right angle bend for that end of the wire to enter a small hole in the fold of its sheets, said right angle bend being formed from the body of its wire with a reverse bend to form a finger grip adjacent the said hole and by which the flexible wire can be manipulated to readily position it in and remove it from the binder, each of said wires being positioned in the fold against longitudinal movement relative thereto solely by its end fitting in said hole and removable from the fold solely by lifting one end out of its hole by its finger grip and pulling the wire longitudinally.

In testimony whereof I have affixed my signature.
